METHOD AND MEANS FOR FLUSHING
DEFECATORS

William C. Groeniger, Columbus, Ohio, assignor
to John B. Pierce Foundation, New York, N. Y.,
a corporation of New York

Application January 4, 1936, Serial No. 57,487

8. Claims. (Cl. 4—69)

My invention relates to an improved method of flushing defecators, i. e. water closets and the like and to means for accomplishing same.

More particularly, my invention relates to the method of flushing a defecator wherein water or a like liquid is utilized as a sanitary agent and wherein air or like fluid under pressure is caused to effect evacuation of same, together with foreign waste matter; and to a defecator embodying means for performance of my stated method.

A primary object of the present invention is to accomplish marked saving in the amount of water or the like for flushing a defecator, maintain a sanitary seal of the defecator under non-flushing conditions, and otherwise conform to the sanitary codes.

To the above and other advantageous ends, my invention contemplates the use of water or like liquid to effect the usual sanitary cleansing of a defecator or like bowl, and also serve as a vehicle for receiving and discharging foreign matter; air or the like under compression when released serving to impart the proper momentum to the water to effectively discharge the water and certain foreign matter through the upflow leg of the bowl by syphonic action.

Advantageously a cycle of operation, during the flushing period, may be employed whereby air under pressure is applied to the contents of the well of the bowl at the same time as, or at a predetermined period of time before or jointly with, the period of supply of water.

Air under pressure is utilized as the momentum imparting agent, i. e., the medium by which force is applied to the contents of the bowl, inclusive of the after-fill and any foreign waste matter contained therein, to impart the requisite momentum for the discharge.

My present invention is also concerned with means for efficiently carrying out the above method, and to this end I provide a defecator bowl, advantageously of the construction disclosed in my co-pending application, Serial No. 749,069, filed Oct. 19, 1934, arranged for the employment of air under pressure pursuant to my present invention.

By my invention, a marked saving of water or like liquid is had. The desirability of such saving is readily appreciated when it is considered that the major proportion of the water consumed by cities is employed for the discharge of defecator waste.

Further details and objects of my invention are more fully disclosed in the following descrip-

tion, and in the accompanying drawings, in which

Fig. 1 is a vertical section of a preferred embodiment of means adapted to carry out my method. Air ducts enclosed within the bowl structure are indicated in dotted lines.

Fig. 2 is a plan view of the embodiment shown in Fig. 1.

Figs. 3, 4 and 5 are vertical sections of the bowl structure shown in Fig. 1, following through a complete operating cycle of my method.

Referring to the drawings particularly Figs. 1 and 2, illustrating a preferred embodiment, 10 indicates a defecator bowl having a construction generally disclosed and claimed in my aforesaid co-pending application.

Such, or equivalent, bowl is preferably of a unitary construction having, inter alia, an upper portion 11 and a lower portion or well 12, and may be supported in any suitable manner as from a wall indicated at 13, for which manner of support the bowl may be provided with a vertical web 14 which extends rearwardly and normal from the main body of the bowl to a vertical back plate or apron 15. A preferred form of support, affording suspension, of the bowl, is disclosed and claimed in my co-pending application, Serial No. 48,860 filed November 8, 1935, entitled Plumbing connection.

As shown, the interior surface of the bowl 10 is preferably of a general conical contour defined in part by the outer wall 10a and in part by the upper surface of the inwardly and downwardly extending ledge 10b, which ledge and its supporting web 10c may be integral parts of the entire bowl structure.

The well 16 leads directly into a trapway or up-flow leg 17 defined between the under surface of the ledge 10b and an under, upwardly extending arcuate portion 10a' of the bowl.

The upper wall portion 11 has at its top a rim formation including an enclosed rim channel 16, extending completely around the bowl periphery and leading from the main chamber 18.

The rim formation partially overhangs the bowl interior. At closely spaced intervals throughout the length of the overhanging portion, and communicating with the rim channel 16, are a plurality of jet openings 16a, such jet openings being preferably small in diameter and directed at an angle to the vertical. The rim channel 16 communicates with the main chamber 18 through its two inlet openings 16b, 16b.

During the flushing period, water or other efflu-

30

30

40

45

55

ent of the nature of water is supplied to the main chamber 18 from a supply pipe 19 communicating with the bowl through an orifice 20, the connection of such supply pipe 19 with the orifice 5 20 being had in any suitable manner. From the main chamber 18, the effluent flows through the two inlet openings 16b, 16b, into the rim channel 16.

During the flushing period, air, or other fluid 10 of the nature of air, under pressure is supplied under suitable control to the main air duct 21, from a suitable compressed air supply line 22. The main air duct 21 leads to the air duct 21a of the vertical air jet opening 23, for initiating 15 and maintaining a vortical movement of the contents 24 of the bowl. The main air duct 21 also leads to the momentum air jet opening 25, disposed and directed in its effective opening in substantial alignment with the well 16 and the 20 entrance of the up-flow discharge leg 17. Preferably, as shown in the drawings, the effective opening of the momentum jet 25 is of relatively flat configuration, the longer dimension of the opening extending co-directionally with the inner surface of the bowl. Also, as shown, the walls of the terminus of the air duct 21 may converge in the direction of flow into the jet opening 25, to enhance the momentum effect.

An evacuator, of any suitable type indicated 30 at 29 connects with the outlet end of the up-flow leg 17, for the discharge of the contents of the bowl. Such evacuator preferably has the construction set forth in my co-pending application Serial No. 48,860, filed November 8, 1935, 35 entitled, Plumbing connection.

Preferably the introduction of water and air to the bowl 10 for initiating and effecting a flushing is had concomitantly. Provision of means to such end may include any suitable arrangement 40 capable of introducing water and air to the bowl and regulating the same in time and other operative relation to each other.

An effective water-air supply arrangement, as 45 illustrated in the drawings, comprises a water valve 34, which includes provision for automatic shut-off after a definite interval of time has elapsed, and a therewith co-ordinated air valve 26, also including provision for automatic shut-off, the same being suitably related to the water 50 supply pipe 19 and the air supply line 22, respectively: such co-ordination in suitable timed relation to each other may be had by means of the jointed-lever arm connection 27, having a conveniently located manual control handle 28.

Figs. 3, 4 and 5 illustrate successive stages of 55 operation of a flushing cycle pursuant to the method of the present invention.

Normally, the well of the defecator bowl is supplied with a body of water 24, termed the after-fill, at a proper sealing level indicated at 30a, determined by the height of the discharge weir 17a of the up-flow leg 17, as appears from Fig. 1.

When it is desired to flush the defecator bowl, the handle 28 is operated to initiate the flushing 65 cycle by opening the water valve 34 and the air valve 26.

The respective valves may be so timed that both open simultaneously or that the water valve may open a predetermined interval in advance 70 of, or subsequent to the instant of opening of the air valve.

In the illustrated instance, see Fig. 3, water from the supply pipe 19, under suitable pressure, flows into the main chamber 18 in advance of the 75 introduction of compressed air, the water enter-

ing and filling the rim channel 16, whereupon the pressure of the water forces it through the respective rim jet openings 16a, about the periphery of the interior walls of the bowl, and in the form of a plurality of jets 31 directed against the side surfaces of the bowl, to exert a quasi-chiseling and/or scrubbing action on any solid waste matter that might have adhered thereto. The direction of discharge of the jets 31 is preferably in conformity to the direction of vortical 10 movement imparted by the air jet 23, in this instance in counter-clockwise direction, as viewed from above in Figs. 2 and 4.

At its predetermined interval, air under pressure is admitted into the duct 21 from the compressed air supply line 22, such compressed air initially causing a forceful discharge of water lodged in the vortical air duct 21a, namely, through the vortical jet opening 23, thus engendering and, thereafter maintaining a vortical 20 movement of the contents 24 of the bowl, indicated by the dotted arrowed line 32, Fig. 4. The air pressure through the air duct 21b causes a forceful discharge through the main jet opening 25, of water lodged in the lower portion of the 25 air duct 21b, thereby initiating and thereafter maintaining a momentum effect upon the water disposed in the well 16, and rectilinearly directed toward and upwardly of the up-flow leg 17, thence over the weir or dam 17a, thence into and 30 through evacuator 29, and eventually into the soil pipe or the like, connected thereto. Such momentum is enhanced by the expansion, see 33, Fig. 4, of the theretofore compressed air stream into the water disposed in the well and in the 35 up-flow leg 17.

The vortical movement imparted to the water by the vortical jet 23 causes solid, and/or semi-solid, and/or floating foreign matter to be positively displaced towards the center of the vortex 40 and positively downwardly within the bowl into the well 16, and directly into the path of discharge of the momentum air jet 25.

Fig. 5 illustrates a final stage of the flushing cycle whereat the foreign waste matter and its 45 environmental after-fill has been discharged from the bowl, and whereat the rim jets continue their flow upon and downwardly of the side surfaces of the bowl to restore the after-fill to proper sealing level, and preparatory to subsequent use 50 and repeated flushing.

From the above it appears that my invention provides for a mass of effluent of the nature of water disposed within the bowl, serving jointly as a seal for the trapway of the bowl and for receiving foreign matter, solid, semi-solid, liquid, etc., and, during the flushing stage, to effectuate the discharge of such contents from the bowl upwardly of the trapway to a soil line or the like by a fluid of the nature of air under compression, 60 and the refilling of the bowl with the stated mass effluent preparatory for subsequent use.

Such refilling of the bowl is advantageously had by the provision of rim openings having their effective discharge directed against the inner sides of the bowl, to thereby remove matter therefrom.

Preferred embodiments of my invention, provide for a vortical movement of the contents of the bowl at an initial stage of the discharge of the 70 contents by the fluid under compression of the nature of the air.

Whereas, I have described my invention by reference to specific forms thereof, it will be understood that many changes and modifica- 75

tions may be made without departing from the spirit of the invention.

I claim:

5. 1. The method of flushing defecators having a bowl provided with a well and trapway arranged to receive an effluent of the nature of water serving as a seal, which includes introducing fluid of the nature of air under pressure to the well of said bowl for discharging the sealing effluent and 10 therein contained contents through a suitable outlet, introducing a predetermined quantity of liquid of the nature of water into said bowl, and terminating the supply of air at a predetermined time before introduction of the said quantity of 15 water or like liquid ceases.
2. A method of flushing defecators having a bowl and a liquid filled well, which includes introducing air or like fluid under pressure to the well of said bowl in the form of a vortical jet 20 and a main discharge jet operative to discharge the contents of said well through a suitable outlet, introducing a predetermined quantity of water or like liquid into said bowl, and cutting off the supply of air or like fluid at a predetermined time before introduction of the said quantity of water or like liquid ceases.
3. A method of flushing defecators having a bowl and a liquid filled well, which includes introducing air or like fluid under pressure to the well of said bowl in a manner operative to discharge the contents of same through a suitable outlet, introducing a predetermined quantity of water or like liquid into said bowl in the form 25 of rim jets, and cutting off the supply of air or like fluid at a predetermined time before introduction of the said quantity of water or like liquid ceases.
4. A method of flushing defecators having a bowl and a liquid filled well, which includes introducing air or like fluid under pressure to the well of said bowl in the form of a vortical jet and a main discharge jet operative to discharge the contents of same through a suitable outlet, introducing a predetermined quantity of water or like liquid into said bowl in the form of rim jets, and cutting off the supply of air or like fluid at a predetermined time before introduction of the 30 said quantity of water or like liquid ceases.
45. 5. A method of flushing defecators having a bowl and a liquid filled well, which includes introducing a predetermined quantity of water or like liquid into the bowl, introducing air or like fluid under pressure to the well of said bowl either at the same time or at a predetermined time after starting to introduce the aforesaid quantity of water or like liquid, and in a manner operative to discharge the contents of said well through a suitable outlet, and cutting off the supply of air or like fluid under pressure at a predetermined time before introduction of the said quantity of water or like liquid ceases.
6. A defecator, including in combination a bowl having a body of liquid such as water maintained therein at a constant level excepting at flushing periods, means for introducing air or like fluid to said bowl to effect evacuation of the contents, means for introducing liquid, such as water, to said bowl, and valves operative to control the introduction of the liquid and the air or like fluid into the said bowl in timed relation to each other.
7. The combination with a bowl provided with an upflow trapway discharge of a chamber for receiving an effluent of the nature of water, rim 25 openings, channel means connecting said rim openings with said chamber, a supply of compressed fluid of the nature of air, a jet opening disposed within the bowl below the level of the effluent serving normally to seal the trapway, and 30 passage means connecting said jet opening with said supply of compressed fluid of the nature of air.
8. The combination with a bowl provided with an upflow trapway discharge of a chamber for receiving an effluent of the nature of water, rim 35 openings, channel means connecting said rim openings with said chamber, a supply of compressed fluid of the nature of air, a jet opening disposed within the bowl below the level of the effluent serving normally to seal the trapway, a second jet opening disposed within the bowl below the normal level of the effluent and directed 40 arcuately relative to the vertical center of the bowl for initiating a vortical movement of the 45 contents of the bowl, and channel means connecting said jet openings with said supply of compressed fluid of the nature of air.

WILLIAM C. GROENIGER.
